UNITED STATES PATENT OFFICE.

THOMAS S. CATLIN, OF WAVELAND, INDIANA, ASSIGNOR TO CATLIN-TOMPKINS CORPORATION OF INDIANA, OF INDIANAPOLIS, INDIANA, A CORPORATION OF INDIANA.

WINDOW-SHADE APPARATUS.

Original application filed February 3, 1922, Serial No 533,795. Patent No. 1,546,565, dated July 21, 1925.
Divided and this application filed June 15, 1925. Serial No. 37,100.

This invention relates to improvements in window shade apparatus, and has for its primary object the sustaining of a window shade in a manner to insure its correct location relative to a window at all times by apparatus characterized by its simplicity and inexpensiveness of production.

A further object is the adaptation of the structure possessing the qualifications above recited to windows of varying sizes.

With these and further objects in view as will in part hereinafter become apparent and in part be stated, the invention comprises certain novel constructions, combinations and arrangements of parts as subsequently specified and claimed.

In the accompanying drawings,—

Figure 1 is a view in front elevation of an apparatus embodying the features of the present invention, parts being broken out for the saving of space.

Figure 2 is a top plan view thereof.

Referring to the drawings by numerals, 1 indicates a substantially U-shaped bracket plate preferably formed of sheet metal, either as a stamping or from a strip of material, the bracket plate being provided with a vertically upwardly opening slot 2 formed transversely in the plate substantially midway of its length and having upstanding legs extending from the portion in which the slot 2 is formed. Said legs terminate in offset portions or feet 3, 3, formed with apertures 4, 4 adapted to receive appropriate anchorage means, such as nails or screws. For purpose of anchorage of said feet to an overhanging portion of a window frame, the legs of the bracket plate 1 may be twisted, as shown in the drawing, to cause the feet 3 to outstand, that is extend in a direction away from each other, but, of course, the presence or absence of such twist is a matter of selection and adaptation to the particular type of window frame.

The bracket plate 1 is thus designed to be anchored to the overhanging portion of the window frame and to depend therefrom in a manner to receive and sustain an engaging pivot from a bracket rod 5. The rod 5 is preferably formed of a strap of metal having midway of its length an offset section 6 disposed to contact with the outer face of the lower portion of the bracket plate 1 and to thus sustain the main portion of the rod

5 spaced from the bracket. A pin 7 extends laterally from the offset portion 6 through the slot 2 and rests against the bottom thereof, and is provided with an appropriate head 8 for retaining the bracket rod 5 in engagement with the bracket plate 1. It is obvious, of course, that the rod 5 may be detached by merely being lifted until the pivot pin 7 is moved vertically upwardly clear of the slot 2. The pin 7 in practice may consist of an appropriate rivet riveted to the rod 5, or otherwise suitably anchored thereto.

The strap-like rod 5 carries a terminal portion 9 at each end, each being a duplicate of the other except for the receiving apertures for the shade roller terminals, as hereinafter stated. Each terminal portion 9 consists of a strip of appropriate material, such as sheet metal, stamped or otherwise formed to shape. Each terminal portion 9 has a section lapping the respective end portion of the rod 5 and slidably engaging the same, a plurality of tabs 10, 10, being formed on each terminal portion 9 and being bent about the respective edge portions of the rod 5 to retain the said rod 5 and respective end portion 9 in engagement while allowing free longitudinal shifting of the respective terminal portion 9 along the engaged portion of rod 5. Each terminal portion 9, beyond the respective end of the rod 5, extends downward and is bent to form a hook-like portion 11 terminating in an upstanding bracket 12. One of the brackets 12 is formed merely with an aperture 85 adapted to receive the usual, extended journal or trunnion 13 of the shade roller 14, while the other bracket 12 is formed with the usual slot for receiving the flat, extended terminal 15 of the shade roller 14, it being understood, of course, that the extended terminal 15 is of the usual construction connected to an internal spring of the well known commercial type for effecting return rotation of the shade roller 14 when it is desired to roll the shade thereon. The bracket plates 12, 12, may, of course, be otherwise apertured or formed as required to receive any particular type of shade roller terminal.

In operation, the bracket plate 1 is anchored to the overhanging portion of the window casing or frame by appropriate anchorage means extended through the aper-

tures 4, and the bracket rod 5 is mounted pivotally on the bracket plate 1. The terminal portions 9 are then adjusted longitudinally with respect to the rod 5, preferably to such location that each terminal portion 9 overlaps the engaged end portion of rod 5 to substantially the same extent as does the other terminal portion 9 so as to produce an exact balance and cause the completed structure to maintain by gravity a substantially horizontal position while resting on the pivot 7. The shade roller 14 with its shade, not illustrated, is then mounted in the bracket plates 12, and the structure is ready for use. It should be noted that if the actuating spring of roller 14 (not illustrated) causes that end of roller 14 to be slightly heavier than the opposite end portion, or if one end portion of the roller 14 with its shade is slightly heavier than the other for any reason, an effective balance can readily be obtained by an appropriate adjustment of the terminal portions 9. The terminal portion 9 at the heavier end portion of roller 14 is merely adjusted slightly from the pivot 7, and the other terminal portion 9 correspondingly adjusted in a direction away from the pivot 7, but at all times such adjustment, when required, will be usually only very slight. Yet, the construction is such as to lend itself effectively to a nicety of balance so that a canted position of the parts will not occur. The shade is operated substantially the same as the ordinary shade, except that should a careless operator cause the shade to assume a slightly angular relation to the roller 14, the parts will adjust themselves by gravity to a balanced position whereas the bracket rod 5 will be slightly out of the horizontal and

the angular position of the shade substantially corrected, but usually the movement of the bracket rod 5 incident to such careless operation will cause the shade to drop to its normal vertical position and allow the supporting parts thereby to assume their normal horizontal position.

This application is a division of my parent application, Serial No. 533,795, filed February 3, 1922, Patent No. 1,546,565, July 21, 1925 and covering improvements in window shade apparatus. Three other divisional applications from said parent application are copending herewith, of which two contain broad claims relative to this application, and this application contains claims sufficiently broad to read upon the showing in the third of said other divisional applications.

What is claimed is:—

1. In window shade apparatus, the combination of a U-shaped bracket plate adapted to have its legs anchored to a horizontal overhanging surface, a flat bracket rod having an offset intermediate portion contacting with and pivotally engaging the bracket plate, and shade roller sustaining means carried by said bracket rod.

2. In window shade apparatus, the combination of a U-shaped bracket plate adapted to have its legs anchored to a horizontal overhanging surface, the plate having a vertical slot opening upwardly intermediate its ends, a flat bracket rod having an offset portion contacting with the bracket plate and pivotally engaging the same through said slot, and shade roller sustaining means carried by said bracket rod.

In testimony whereof I affix my signature.

THOMAS S. CATLIN.
